UNITED STATES PATENT OFFICE.

ARCHIBALD F. REDDIE, OF PHILADELPHIA, PENNSYLVANIA, ASSIGNOR TO
McCALLUM & McCALLUM, OF SAME PLACE.

DESIGN FOR CARPET.

SPECIFICATION forming part of Design No. 25,464, dated May 5, 1896.

Application filed March 30, 1896. Serial No. 585,492. Term of patent 3½ years.

To all whom it may concern:

Be it known that I, ARCHIBALD F. REDDIE, a citizen of the United States, residing at the city of Philadelphia, in the county of Philadelphia and State of Pennsylvania, have invented and produced a new and original Design for a Carpet or other Fabric, of which the following, taken in connection with the accompanying drawing, is a specification.

10 In the accompanying drawing, A is the body, B the border, and A B a complete carpet; and said drawing conveys to the eye the effect or pattern which constitutes my design and imparts a peculiar or distinctive appearance 15 to the carpet to which it is applied.

The leading or characteristic feature or features of my design may be said to comprise the distinct or separated bunches *a* of flowers arranged upon a solid background *b*, 20 as shown. In the drawing these bunches *a* of flowers are associated with the bands *c* and

d, of which the band *d* is decorated with the ornamental things *e* and *f*.

Obviously my design for a pattern may be applied to or wrought in Wilton, Brussels, 25 velvet, or other carpet in such colors or combinations of colors as may be desired.

What I claim as new, and desire to secure by Letters Patent, is—

1. In the design for a carpet the body A, 30 substantially as shown.
2. In a design for a carpet the border B, substantially as shown.
3. The design for a carpet consisting of the body A, and the border B, substantially as 35 shown.

In testimony whereof I have hereunto signed my name.

ARCHIBALD F. REDDIE.
